UNITED STATES PATENT OFFICE.

CYRUS R. HOWARD AND JOHN A. HELLSTROM, OF JOHNSTOWN, PENNSYLVANIA; SAID HOWARD ASSIGNOR TO WILLIAM W. HOFFMAN, OF SAME PLACE.

CURLING-IRON.

SPECIFICATION forming part of Letters Patent No. 532,066, dated January 8, 1895.

Application filed October 30, 1894. Serial No. 527,448. (No model.)

To all whom it may concern:

Be it known that we, CYRUS R. HOWARD and JOHN A. HELLSTROM, of Johnstown, county of Cambria, State of Pennsylvania, have invented certain new and useful Improvements in Curling-Irons, of which the following specification is a true and exact description, due reference being had to the accompanying drawings.

10 Our invention consists in an improved form of curling irons, whereby certain advantages are gained as hereinafter set forth and described with the aid of the drawings, in which—

15 Figure 1 is a general view of a pair of curling irons embodying our invention. Fig. 2 shows them folded together. Fig. 3 shows the handles opened half way for a purpose hereinafter explained. Fig. 4 is a vertical 20 section through the pivot of the handles, and Fig. 5 is a top view showing the handle in section.

In general the construction of the curling irons is as follows:

25 I and I are the irons, the one substantially round and the other hollowed out to partially surround it when they are together. These irons are not pivoted together as is customary but their rear ends are rigidly secured to 30 either end of the bent spring S as is clearly shown in Fig. 5, in which $\bar{l}$ are side lugs formed on the iron near the rear end and closed down upon the spring after it has been placed in position between them. This spring 35 is substantially U shaped, that is, its two extending members do not cross each other but are secured to the irons with which they approximately align. By this construction the jaw or opening between the opposing members of the curler is extended clear back to the rear of the spring.

The handles H are secured to the irons as follows: Upon the irons and near their rear ends are formed the ears e between which is 45 pivoted on pivot p the shank h of handle H. The end of the shank is formed flat and the ends of spring S are bent up to engage it and hold it in either of the three positions as will be readily seen in Fig. 4. The handles may

thus be folded along the irons or backward 50 into operative position. When folded backward they engage the spring at its rear end, thus using it as a fulcrum upon which to force the extending portions of the spring carrying the irons apart.

We preferably form the handles H as shown in Fig. 2 having the metallic ferrule f which when the handles are folded comes in contact with the iron and having the remainder of the handle, which may be of wood or other 60 non conductor of heat, so formed as not to come in contact with the iron and thus we prevent any charring or burning of the handles by contact with the iron when heated. Likewise when the handles are opened for 65 use, these ferrules come in contact with the spring S and so save the wooden portion of the handles.

By the use of the spring S, of the shape shown, we gain many advantages over those 70 curlers in which the irons are pivoted together, or those in which the shanks of the irons cross one another, as the irons in our curler may be separated for their entire length, nor is there any danger of the hair 75 becoming caught or tangled between the opposing members of the iron, as there are no parts playing upon or past one another. This absence of joints or niches in which the hair is liable to catch is a very desirable feature in our form of curler.

As the function of the spring S is to form a hinge upon which the irons may swing and also to close the irons together, this spring should be of the proper strength to press the 85 irons together with the desired pressure. We have shown it with a comparatively larger return bend at the rear end. This is preferable as it leaves plenty of room between the ends of the spring, but of course the bend 90 might be short and the two halves of the spring closer together.

By pivoting the handles so that they may be folded along the iron, the curler is rendered more compact and more easily carried. 95 The handles when half open afford a support by which they may be held over any heating device, as in a lamp chimney.

Having thus described our invention, what we claim, and desire to protect by Letters Patent, is—

1. A curling iron comprising the two irons hinged together at their rear ends by means of a substantially U shaped spring, each end of which is rigidly secured to one of the irons, and a pair of handles separate from the spring, which handles are pivotally attached one to each iron near its rear end.
2. A curling iron comprising the two irons hinged together at their rear ends by means of a substantially U shaped spring, the two arms of which spring are rigidly secured one

to each iron and extend backward substantially in alignment therewith, and a pair of handles separate from said spring, said handles being pivotally attached one to each iron near its rear end so as to fold along the iron or backward against the spring into operative position.

In testimony whereof we have affixed our signatures in presence of two witnesses.

CYRUS R. HOWARD.

JOHN A. HELLSTROM.
